G. LIDSEEN

OIL CAN

Filed Oct. 9, 1926

INVENTOR

Gustave Lidseen

Charles G. Hill Atty's

UNITED STATES PATENT OFFICE.

GUSTAVE LIDSEEN, OF CHICAGO, ILLINOIS.

OIL CAN.

Application filed October 9, 1926. Serial No. 140,444.

This invention relates to an oil can and more particularly to a can provided with a removable spout having a valve mounted therein adapted to be operated by means of a pivoted lever mechanism to cause opening of the valve when the oil can is inverted to permit oil to be discharged out of the outer end of the spout.

It is an object of this invention to provide 10 an oil can having a valve mechanism mounted in the spout thereof adapted to be opened by depressing a control lever.

It is also an object of this invention to provide an oil can having a removable cover and 15 spout, said spout having a spring controlled valve mounted therein adapted to be actuated by means of a pivoted lever to permit oil to be discharged from the spout when the oil can is inverted.

20 It is an important object of this invention to provide an oil can with an improved cover and spout having a control valve mounted within the spout intermediate the ends thereof and operable by means of a pivoted lever 25 against the resistance of a spring which normally holds the valve in closed position.

Other and further important objects of 30 this invention will be apparent from the disclosures in the specification and the accompanying drawings.

This invention (in a preferred form) is illustrated in the drawings and hereinafter more fully described.

On the drawings:

35 Figure 1 is a side elevation of an improved oil can embodying the principles of this invention.

Figure 2 is an enlarged fragmentary elevation of the cover and spout removed from 40 the can with parts shown in section to illustrate the valve mechanisms.

Figure 3 is a fragmentary longitudinal section of the lower portion of the spout illustrating the valve mechanisms in depressed position to open the valve.

45 Figure 4 is an enlarged bottom plan view of the oil can cover.

As shown on the drawings:

The reference numeral 1 indicates a can or 50 container provided with a handle 2 and with a flanged neck 3. Removably engaged on the neck 3 is a spout cap comprising a cover 4, the margin of which is bent to form a rim 5. Diametrically disposed arc shaped flanges 6 are integrally formed on the cover

rim 5 to permit the cover to be removably engaged on the neck 3 of the can 1. A gasket or packing ring 7 is provided in the cover rim 5 to form a tight joint between the flanged neck 3 and the cover 4. Integrally 60 formed on the cover 4 is a cylindrical shell or casing 8 having rigidly secured therein by soldering or other suitable means the lower enlarged end of a tapered oil discharge spout 9.

Securely mounted within the spout 9 intermediate the ends thereof is a passaged valve seat or sleeve 10, the lower end of which serves as a seat for a control valve head 11 which when in closed position, as illustrated in Figure 2, closes the discharge opening 12 thereby preventing oil from being discharged from the spout 9. The valve head 11 is securely mounted on the upper end of the valve stem 13 which extends downwardly through the spout and has the lower end or arm 14 bent at an angle to project downwardly through the cylindrical casing 8 and the cover 4. Secured on the upper end of the arm 14 adjacent the point where the arm joins the valve stem 13 is a plate or disk 15 against which the upper end of a coiled control spring 16 is engaged. The spring 16 is of spiral shape with the enlarged lower coil seated within a cylindrical cup 17 which is rigidly secured within the lower end of the shell or casing 8 to provide a support for the spring. Struck from the bottom of the cup 17 is a downwardly directed flange 18, the lower end of which is bent outwardly to afford a retaining lug 19.

Pivotedly supported on the flange 18 is a lever 20 one end of which is notched at 21 to receive the lower end of the valve stem arm 14. Normally the spring 16 seated within the cup 17 acts on the disk 15 to resiliently hold the valve 11 in its closed position seated against the valve seat 10 to close the discharge opening 12.

The lever 20 is adapted to be actuated by means of a handle mechanism comprising a curved yoke arm 22 one end of which is in contact with the outer end of the lever 20. Integrally formed on the yoke arm 22 is a curved lug or finger 23 which serves to hold a spring washer plate 24 seated in position against the lower convex surface of a slotted socket 25 formed in the cover 4. Movably seated within the socket 25 to cover the slot therein and afford a non-leaking joint, is a

curved rocker or semi-spherical plug 26 having an inclined air passage or vent 27 formed therein to permit air to pass through the cover into the can 1 when the valve 11 is in open position so that the oil within the can may be discharged through the valve seat 10 and out of the end of the spout 9. Secured to the passaged rocker 26 is a finger piece or outer lever 28 having a projection or arm 29 integrally formed thereon which projects through the rocker and through the socket 25 to permit the lower end of said arm 29 to be bent over in the form of a hook 30 to engage the yoke-shaped arm 22 to hold the same in operative position. As illustrated in Figure 2 the spring 16 normally acts to actuate the inner lever 20 to cause the same to hold the finger piece 28 in a raised position with the air vent 27 of the rocker 26 moved into a position shutting off communication with the interior of the can 1.

The operation is as follows:

The oil can 1 is adapted to be filled with oil when the cover 4 and spout 9 are removed from the can. After the can has been filled with oil the cover may be locked in position on the neck 3 of the can by friction lugs or any similar retaining means ordinarily used in oil cans of the type hereinbefore described.

Normally the finger piece 28 is resiliently held in an elevated position, as shown in Figure 2, by the action of the spiral spring 16 which acts on the inner lever 20 which in turn acts on the yoke-shaped arm 22 and the finger piece extension 29 to hold the passaged rocker 26 and the finger piece 28 in the positions illustrated in Figure 2. With the control valve 11 held in closed position against the valve seat 10 leakage of oil from the spout 9 is prevented in case the oil can is accidentally overturned or is left lying on its side.

To use the oil can, the same is turned to one side or inverted with the mouth of the spout 9 engaged in or upon a device or mechanism requiring lubrication. The oil in the can is then permitted to flow through the opening in the bottom of the cup 17 into the casing or shell 8 and then into the lower portion of the spout 9 below the valve 11. The finger piece 28 may now be depressed thereby rotating the rocker 26 so that the air vent 27 is positioned, as illustrated in Figure 3, to permit air from the exterior of the oil can to enter the cover and the upper portion of the oil can 1. With the depression of the finger piece 28 the yoke-shaped arm 22 is actuated by the finger piece extension 29 to cause the inner lever 20 to be pivoted on the flange 18 into the position illustrated in Figure 3. With the downward movement of the inner end of the inner lever 20 the valve stem arm 14 and the valve stem 13 are pulled downwardly within the spout

9 against the action of the coiled spring 16 which is compressed. Downward movement of the valve stem or stopper rod 13 causes the valve head 11 to move inwardly away from the passaged valve seat 10 thereby opening the discharge passage 12 and permitting the oil trapped in the lower portion of the spout 9 to be discharged through the outer end of the spout.

When the finger piece 28 is released the spring 16 acts automatically to return the valve head 11 to its normal closed position seated against the valve seat 10. With the closing of the valve the inner lever 20 and the finger piece 28 are simultaneously returned to their normal positions, while the passage rocker 26 is moved to shut off the air passage 27.

I am aware that many changes may be made, and numerous details of construction may be varied through a wide range without departing from the principles of this invention, and I therefore do not purpose limiting the patent granted hereon, otherwise than necessitated by the prior art.

I claim as my invention:

1. An oil can comprising an oil container, a spout thereon having a flange for attachment to the container top, a passaged valve seated in said spout, a valve stem in said spout, a valve head on one end thereof, a cup secured in said spout, a disk secured on said valve stem, a coiled spring engaged around the valve stem between said cup and said disk adapted to normally hold the valve head seated in closed position against the valve seat, an inner lever pivotally supported on said cup, and an outer lever pivotally supported on the spout flange and having one end thereof engaged against the inner lever and the other end projecting from the spout flange to afford a means for opening the valve head against the action of said spring.

2. In an oil can of the class described the combination with a spout, of a supporting cover therefor, a passaged valve seat mounted in said spout, a cup secured in said spout, a valve stem movably mounted in said spout, a valve head on one end of said valve stem, a spring in said cup connected with said valve stem adapted to normally hold the valve head seated against said valve seat to close the same, a projection struck from said cup, an inner lever pivotally supported on said projection and connected with the lower end of said valve stem, a passaged rocker supported on said cover, and an outer lever connected with said rocker and projecting through the cover to contact said inner lever to actuate said inner lever when the outer lever is depressed to cause the valve head to be moved away from said valve seat to permit oil to be discharged from the spout.

3. An oil can comprising a container, a

cover removably engaged thereon, a spout on said cover, a passaged valve seat in said spout, a valve stem, a valve head on one end of said valve stem; a cup secured in said spout, a disk secured on said valve stem above said cup, a coiled spring engaged around said valve stem, between the cup and said disk, an arm struck from said cup, an inner lever pivotally supported 10 on said arm and connected with the lower end of the valve stem below said cup, a passaged socket formed in said cover, a passaged rocker seated in said socket, an outer lever secured to said rocker and projecting through the cover, and a yoke-shaped 15 member supported on the inner end of said outer lever and contacting the inner lever to permit the valve head to be moved into open position against the action of said spring when the outer lever is depressed to cause 20 actuation of the inner lever by said yoke-shaped member.

In testimony whereof I have hereunto subscribed my name.

GUSTAVE LIDSEEN.
